The ornamental design for a recyclable aluminum drinking glass, as shown and described.

DESCRIPTION

FIG. 1 is a perspective view of the recyclable aluminum drinking glass showing my new design according to a first embodiment;

FIG. 2 is a front elevational view of the first embodiment, the right side, left side, and rear elevational views of the first embodiment being the same as the front elevational view of the first embodiment;

FIG. 3 is a top plan view of the first embodiment;

FIG. 4 is a bottom plan view of the first embodiment;

FIG. 5 is a sectional view of the first embodiment taken along line 5-5 of FIG. 2;

FIG. 6 is a perspective view of the recyclable aluminum drinking glass showing my new design according to a second embodiment, the second embodiment being identical to the

first embodiment except that the second embodiment is shown with a symbolic break in its length. The appearance of any portion of the article between the break lines forms no part of the claimed design.

FIG. 7 is a perspective view of the recyclable aluminum drinking glass showing my new design according to a third embodiment;

FIG. 8 is a front elevational view of the third embodiment, the right side, left side, and rear elevational views of the third embodiment being the same as the front elevational view of the third embodiment;

FIG. 9 is a top plan view of the third embodiment;

FIG. 10 is a bottom plan view of the third embodiment;

FIG. 11 is a sectional view of the third embodiment taken along line 11-11 of FIG. 8;

FIG. 11a is an enlarged view of a portion of FIG. 11;

FIG. 12 is a perspective view of the recyclable aluminum drinking glass showing my new design according to a fourth embodiment, the fourth embodiment being identical to the third embodiment except that the fourth embodiment is

shown with a symbolic break in its length. The appearance of any portion of the article between the break lines forms no part of the claimed design.

FIG. 13 is a perspective view of the recyclable aluminum drinking glass showing my new design according to a fifth embodiment;

FIG. 14 is a front elevational view of the fifth embodiment, the right side, left side, and rear elevational views of the fifth embodiment being the same as the front elevational view of the fifth embodiment;

FIG. 15 is a top plan view of the fifth embodiment;

FIG. 16 is a bottom plan view of the fifth embodiment;

FIG. 17 is a sectional view of the fifth embodiment taken along line 17-17 of FIG. 14; and,

FIG. 18 is a perspective view of the recyclable aluminum drinking glass showing my new design according to a sixth embodiment, the sixth embodiment being identical to the fifth embodiment except that the sixth embodiment is shown with a symbolic break in its length. The appearance of any portion of the article between the break lines forms no part of the claimed design.
